UNITED STATES PATENT OFFICE

JOSEPH J. BLACK, OF AKRON, OHIO, ASSIGNOR TO THE B. F. GOODRICH COMPANY, OF NEW YORK, N. Y., A CORPORATION OF NEW YORK

DESIGN FOR A TIRE

Application filed October 11, 1932. Serial No. 45,307. Term of patent 14 years.

To all whom it may concern:

Be it known that I, JOSEPH J. BLACK, a citizen of the United States, residing at Akron, in the county of Summit and State of Ohio, have invented a new, original, and ornamental Design for a Tire, of which the following is a specification, reference being had to the accompanying drawing, forming a part thereof.

Fig. 1 is a plan view of a section of a tire

showing my new design, the complete tire being of annular form.

Fig. 2 is a side elevation of the same, and
Fig. 3 is a transverse section on line 3—3
of Fig. 1.

I claim:

The ornamental design for a tire as shown
and described.

JOSEPH J. BLACK.
